UNITED STATES PATENT OFFICE.

EDWIN J. McILVRIED, OF BAY VILLAGE, OHIO.

INSULATOR CAP.

Application filed June 12, 1925. Serial No. 36,639.

This invention relates to improvements in the art of making insulator caps adapted to be employed in supporting high tension conductors, and pertains more especially to an improved process of making an insulator cap having means at the top thereof for a supporting connection and also having means for engaging and supporting cement which secures the head of an insulator within the cap.

10 I am aware that cast metal insulator caps have heretofore been made, and also that insulator caps have been made from blank metal bars by forging, punching, metal-extruding and bending operations.

15 The manufacture of an insulator cap from a blank metal bar requires operations which incur much and rapid wear and tear on the tools or apparatus employed in the forging of said bar into the form of said cap and renders 20 the apparatus short-lived and thereby enhances the cost of manufacture of the cap.

25 One object of my invention is to devise an improved process which is not only highly practical for the production of an insulator cap superior to and more reliable than a cast metal cap but which does not involve the use of a blank bar and minimizes the wear and tear on the apparatus employed in carrying out said process.

30 Another object is to devise a process whereby the formation of cracks, orifices or pores in the bell-shaped body of the cap and other detrimental or objectionable defects are positively prevented.

35 Another object is to facilitate the economical manufacture of the desired insulator cap from a piece of tubular metal stock.

With these objects in view, and to attain other objects hereinafter appearing, this invention consists in the improved steps or process hereinafter described and pointed out in the claims.

40 In the accompanying drawings, Figure 1 is a central vertical section of a tubular shell adapted to be operated on, as will hereinafter appear, for the production of the desired insulator cap and having opposite end portions thereof unequal in diameter. Fig. 2 is a top plan in relation to Fig. 1. Fig. 3 is a bottom plan in relation to Fig. 1. Fig. 4 is a central vertical section of a set of dies for operating on the hereinbefore mentioned shell which is shown suitably positioned, in Fig. 4, in relation to said dies. Fig. 5 is a side view, largely in central section, showing said shell confined for operation thereon by said dies. Fig. 6 is a bottom view of the movable dies illustrated in the upper portion of Fig. 4. Fig. 7 is a top plan of the die illustrated in the lower portion of Fig. 4. Fig. 8 is a side view, largely in section, illustrating the forging, by said dies, of a transverse partition adjacent the inner end of the diametrically smaller end portion and internally of the hereinbefore mentioned shell. Fig. 9 is a central horizontal section of a pair of horizontal dies for operating on the partitioned shell shown held between said dies, and shows a portion of a movable die for subsequently entering said shell at the diametrically larger end portion of the shell. Fig. 10 is a vertical section taken along line 10—10 in Fig. 9. Fig. 11 is a view illustrative of the inner side of a die of the pair of dies illustrated in Fig. 9. Fig. 12 is a right-hand end view in relation to Fig. 11. Fig. 13 is a central horizontal section showing the dies of the pair of dies illustrated in Fig. 9 as closed together and as having operated on the diametrically smaller end portion of the partitioned shell, and the shell-entering die adjacent said pair of dies is shown, in Fig. 13, as in position to enter said shell. Fig. 14 is a vertical section taken along line 14—14 in Fig. 13. Fig. 15 is a vertical section taken along line 15—15 in Fig. 14. Fig. 16 is a central horizontal section illustrative of the cooperation of the dies illustrated in Fig. 13. Fig. 17 is a vertical section taken along line 17—17 in Fig. 16. Fig. 18 is a vertical section taken along line 18—18 in Fig. 17. Fig. 19 is a central vertical section of the partitioned shell formed by the operation of the hereinbefore mentioned dies on the tubular shell shown in Figs. 1, 2, 3, 4 and 5, and shows said shell in an upright position and also shows the completion of the bell-shaped body of an insulator cap. Fig. 20 is a central vertical section illustrative of trimming operations to be performed on the upper and diametrically smaller end portion of the shell shown in Fig. 19. Fig. 21 is a vertical section taken along line 21—21 in Fig. 20. Fig. 22 is a central vertical section of a finished insulator cap made by my improved process. Fig. 23 is a central vertical section taken along line 22—22 in Fig. 1, and

shows said finished cap applied to the head of an insulator. Portions are broken away in the drawings to reduce their size.

In said drawings, Figs. 1, 2 and 3 illustrate a tubular metal shell A preferably made of steel and adapted to be operated on, as will hereinafter appear, to produce the desired insulator cap. One end portion 25 of said shell is diametrically smaller internally and externally than and substantially in line endwise with its other and diametrically larger end portion 26, and said shell is preferably substantially circular externally and internally from end to end. The larger end portion 26 of said shell preferably measures considerably more, both in external and internal diameter, than the smaller end portion 25 which is adapted to be operated on, as will hereinafter appear, to participate in the formation of the top of the bell-shaped body of the cap to be produced as well as to form a supporting connection for said top, and said shell is shown as comprising an intermediate portion 27 which flares from the inner end of the smaller end portion 25 toward the larger end portion 26, and said portions 26 and 27 are adapted to participate in the formation of said body of said cap. The larger end portion 26 of the shell A is preferably substantially uniform in thickness from end to end. The smaller end portion 25 of said shell is preferably substantially uniform in thickness from end to end and thicker than the larger end portion 26. The intermediate portion 27 of the shell A preferably increases in thickness from the larger end portion 26 to the smaller end portion 25. The smaller end portion 25 and the intermediate portion 27 of the shell A are produced hot to render them suitable for subjection to forging operations, and the diametrically larger end portion 26 is preferably comparatively cool.

The shell A illustrated in Figs. 1, 2 and 3 is preferably produced by the required forging operations on a hot steel tube which is uniform in diameter from end to end and measures about the same in length as said shell A and about the same in diameter and thickness as the larger end portion 26 of said shell, and said tube preferably consists of a piece cut from tubular metal stock which measures substantially the same in diameter and thickness as said larger end portion of said shell.

The shell A, having been produced, is mounted (see Fig. 4) on the bottom die B of a set of three steel dies, and the other two dies C and D of said set of dies are movable vertically and shown, in Fig. 4, as spaced upwardly from the relatively stationary die A.

The bottom die B (see Figs. 4 and 7) comprises a substantially vertical steel body 29 having a circular base 30 rendered stationary

in any approved manner, and said body (see Figs. 5 and 7) is circular from said base to its upper extremity, and externally provided, at its lower end portion (see Figs. 4, 5 and 7) with an upwardly facing horizontal shoulder 31 forming a seat for the end face of the diametrically larger end portion 26 of the shell A. The upper portion of the die-body 29 tapers upwardly, as at 32, to conform to the internal surface of the intermediate portion 27 of the shell A, and said body is substantially uniform in external diameter between said tapering portion and the shoulder 31. The die-body 29 has a central hole 33 extending vertically through said body, and the upper end portion 34 of said hole flares upwardly at its upper end, as shown in Fig. 4, to form a seat for the head 36 of a work-ejecting rod 35 engaging said hole and adapted to be operated in any approved manner. The head 36 has an upper conical portion 37 the circumferential surface of which is flush with the circumferential surface of the tapering portion 32 of the die-body 29, and said portion of said head therefore forms an upward extension of said tapering portion of said body and conforms to the diametrically smaller portion of the internal surface of the intermediate portion 27 of the shell A.

In Fig. 4 the shell A is shown seated, at 95 the end face of its diametrically larger end portion 26, on the shoulder 31, and said portion of said shell embraces the body 29 of the die B below the tapering portion 32 of said body, and the intermediate portion 27 of said 100 shell embraces said tapering portion of said body and the conical portion 37 of the head 36, and the diametrically smaller end portion 25 of said shell is substantially wholly above said die.

The two movable dies C and D of the set of dies shown in Fig. 4 are disposed the one D around the other C and externally circular in end view as shown in Fig. 6, and the inner die C of said movable dies is a solid vertical 110 cylindrical body in line endwise with the relatively stationary die B. The dies C and D are movable endwise independently of each other or together, and the outer die D of said movable dies consists of a vertically disposed annular block which has a lower end portion 38 arranged and internally sized as required to completely embrace the larger end portion 26 of the shell A when said shell has been seated on the shoulder 31, as shown in 115 Figs. 4 and 5. In Fig. 5 the lower end portion 38 of the annular movable die D is shown as embracing the larger end portion 26 of the seated shell A, and said die has a downwardly flaring internal surface 39 extending 120 upwardly from the lower end portion 38 of said die and shown, in Fig. 5, as extending from end to end and closely and completely embracing and conforming to the intermediate portion 27 of said shell. Also, the 125

upper portion of the outer movable die D is uniform in internal diameter from the upper end of said flaring surface 39 to the upper extremity of said die and adapted to completely cover the outer circumferential surface of and closely embrace the smaller end portion 25 of the shell A when the blank is seated on the shoulder 31, as shown in Fig. 5, and said upper portion of said die extends upwardly from said flaring surface far enough not only to embrace said end portion of said shell from end to end of said portion of said shell but to form a guideway, above the seated shell, for the inner movable die C. Said inner movable die has a cylindrical lower end portion 41 which is diametrically smaller than the remainder of the die and in line vertically with the relatively stationary die B and therefore aligned vertically with the smaller end portion 25 of the shell A when the blank has been seated on the shoulder 31. The portion 41 of the die C measures less in diameter than the external diameter of the smaller end portion 25 of the shell A and more than the internal diameter of said portion of said shell. Fig. 5 shows the inner movable die C as having been lowered into a position in which it is about to enter the hot smaller end portion 25 of the shell A when the outer movable die D has been lowered and embraces the larger end portion 26 of said shell, as shown in Fig. 5, and then the inner movable die C is forcibly moved into the diametrically smaller end portion 25 of said shell, as shown in Fig. 8, to a point at which its portion 41 is only spaced from the upper extremity of the portion 36 of the bottom die a distance measuring about the same as the thickness of the larger end portion 26 of said shell. During the downward movement of said inner die C in relation to the smaller end portion 25 of the shell A, as shown in Fig. 8, metal is displaced at the interior of and from said end portion of said shell toward the diametrically smaller end of the intermediate portion 27 of said shell and to and between the face of the end portion 41 of said inner die and the portion 36 of the bottom die B so as to increase the internal diameter of the smaller end portion of the shell A, as shown in Fig. 8, and so as to effect the formation of a substantially imperforate transverse partition 42 internally of said shell adjacent the inner end of said smaller end portion of said shell, and 43 indicates the chamber formed internally of said smaller end portion of said shell between said partition and the outer end of said portion of said shell. Obviously the partition 42 obstructs communication between said chamber 43 and the chamber 44 formed internally of the shell at the opposite side of said partition.

The hereinbefore mentioned dies, and the other dies hereinafter mentioned, are sup-

ported and operated in any approved manner. Die-supporting means and die-operating mechanism are too well known, however, to require description and illustration in this specification.

When the partition 42 has been formed internally of the shell A, as illustrated in Fig. 8, the movable dies C and D are withdrawn from said shell the distance required to permit lifting of said shell from the bottom die A. Then the member 35 of said bottom die is elevated the distance required to remove said shell from the body 29 of said bottom die, and the removed shell is mounted or supported, at its smaller end portion 25, (see Figs. 9 and 10) on an end portion of a flat steel bar or member E which is inserted into said portion of said shell centrally between opposite sides of the shell and extends into and from end to end of the chamber 43 in said portion of said shell and abuts, at its inner extremity, against the partition 42, as shown in Fig. 9. As the portion 41 of the inner movable die C is cylindrical and as the outer movable die D is internally circular in end view obviously the smaller end portion 25 of the shell A remains circular externally during the formation of the partition 42 and the chamber 43 is circular in cross-section as shown in Fig. 10. The supporting member E is oblong in cross-section, as shown in Fig. 10, and has opposite sides thereof flat and has two outwardly transversely curved longitudinal edges conforming, as at 46 in Fig. 10, to the circular surrounding wall of said chamber.

In solid lines in Fig. 9 the partitioned shell A is shown held in position horizontally between and parallel with the dies of a pair of oppositely disposed horizontal and parallel dies G and H, and the die G is movable laterally toward and from the die H which is rendered stationary in any approved manner, and said dies are adapted to extend circumferentially of opposite longitudinal halves respectively of the aforesaid shell.

Each die of the pair of dies G and H (see Figs. 9, 11, and 12) has a cavity 48 formed at the laterally facing inner side of the die and spaced from the top and bottom of said die and extending from one end of said die toward the opposite end of the die more than one-half of the length of the die and spaced from the last-mentioned end of the die and adapted to be engaged by the larger end portion 26 and intermediate portion 27 of the partitioned shell A and by the inner end of the smaller end portion 25 of said shell. The cavities 48 in the dies G and H are directly opposite each other. Each die of said pair of dies G and H is shown internally provided, at the inner end of its cavity 48, (see Figs. 9, 11, 12, 14 and 15) with the two lugs 50 formed at the top and bottom respectively of said end of said cavity, and a recess 51

is formed at the inner side of and in said die centrally between the top and bottom of the die and between the last-mentioned end of the die and said lugs and spaced from the top and bottom of the die and extends from said lugs toward said last-mentioned end of the die somewhat less than half the distance between said end of the die and said lugs. The recesses 51 in the dies G and H are directly opposite each other. Each die of the pair of dies G and H also has a recess 52 formed at the inner side of and in said die centrally between the top and bottom of the die and extending to the last-mentioned end of the die from the recess 51 in said die. The recesses 52 in the dies G and H are directly opposite each other.

In dotted lines in Fig. 9 the partitioned shell A is shown as having been actuated laterally toward and partially into the cavity 48 and recess 51 in the stationary die H. The lugs 50 of each die of the pair of dies G and H (see Figs. 11, 12 and 15) are spaced far enough apart to prevent indentation of the smaller end portion 25 of said shell by said lugs during the actuation of the die G toward and against the die H. The recesses 52 in the dies G and H have the arrangement and dimensions required to accommodate the location of the shell-engaging member E when the die G has been moved against the die H, as shown in Figs. 13 and 15. The recesses 51 (see Figs. 9 and 12) are deeper and wider than the recesses 52. The recess 51 in each die of the pair of dies G and H measures less from end to end than the smaller end portion 25 of the partitioned shell to be operated on by said dies. Said shell, when it has partially entered the stationary die H, as shown in dotted lines in Fig. 9, is positioned with the outer end of its smaller end portion 25 next to the inner end of the recess 52 in said die.

The recess 51 in each die of the pair of dies G and H (see Fig. 9) has a depth which measures less than half the diameter of the smaller end member 25 of the partitioned shell before the operation on said shell by said dies, and therefore the laterally facing upright walls 53 of said recesses, during the actuation of the die G toward and against the die H, press those portions of said member 25 which are between the member E and said walls 53 against the laterally facing sides of said member E and thereby flatten said portions of said member 25, as shown in Figs. 13 and 14, and said recesses are wide enough to permit displacement of metal, as at 54 in Figs. 14 and 15, toward the top and bottom walls of said recesses during said operation of said dies.

The cavities 48 in the dies G and H (see Fig. 13) are large enough in dimensions to permit diametrical or transverse expansion of the larger end portion 26 and intermediate portion 27 of the partitioned shell when the

smaller end portion 25 of said shell has been flattened. While said shell is confined by the dies G and H after the flattening of said smaller end portion of said shell a movable die I, adapted to be employed in expanding the larger end portion 26 and intermediate portion 27 of said shell and shown in Fig. 13 as arranged to be actuated into said larger end portion of said shell, is actuated into said shell and against the adjacent side of the partition 42, as shown in Figs. 16 and 18, and the member E remains held against the opposite side of said partition during the shell-expanding operation of said die. The external contour and the diametrical or transverse dimensions of the movable die I, in relation to the dimensions of the cavities 48 in the dies G and H, are such that said die I, during its movement toward and against the partition 42, diametrically expands the partitioned shell from said partition to the outer end of the diametrically larger end portion of the shell and against the walls of said cavities. Obviously the partition 42 forms a portion of the bell-shaped body of the insulator cap 90 being made, and the formation of the remainder of said body is substantially or largely completed during the hereinbefore mentioned shell-expanding operation of the die I, and obviously said die and the walls of the cavities 48 in the dies G and H cooperate in pressing the portions 26 and 27 of the partitioned shell into the form desired for the formation of said body, as shown in Figs. 16 and 18.

After the shell-expanding operation of the die I, the dies G and I are withdrawn from the expanded shell to permit removal of said shell from the die H and member E, and Fig. 19 shows the removed shell in an upright position with its smaller end portion 25 uppermost and also shows an inwardly projecting annular flange 55 formed at the lower end of and on the aforesaid bell-shaped body. Said smaller end portion of said shell is trimmed and thereby externally contoured as indicated by the dotted lines at 56 in Fig. 19 and as shown in solid lines in Fig. 20. Said trimming of the smaller end portion 25 of said shell results in the formation of two laterally spaced upwardly projecting members 110 57 connected at their inner end portions by spaced webs 58, and said webs are then cut away by a milling tool or otherwise, and then the members 57 are perforated, as at 59 in Figs. 22 and 23, as required to form upwardly projecting registering ears which constitute a supporting connection for the resulting finished cap.

The insulator cap illustrated in Fig. 22 is shown applied, in Fig. 23, to the head 61 of an insulator K, and said head is contained within the bell-shaped body of the cap and secured in place within said body by cement 62 from the flange 55 of the cap to and over said head.

internally of said shell and thereby forming a portion of the body of an insulator cap, then pressing the shell between said partition and the outer end of the diametrically smaller end portion of the shell into the form of a flattened hollow member having substantially flat opposite portions, and then finishing

the formation of the body of the insulator cap and operating on said flattened hollow member as required to form the desired supporting connection for said cap. 10

In testimony whereof, I sign the foregoing specification.

EDWIN J. McILVRIED.
